United States Patent Office

Des. 221,896
Patented Sept. 14, 1971

221,896

FERTILITY TIMING CALCULATOR

James E. Richardson, Weston, Conn., assignor to Cambridge Research and Development Group, Westport, Conn.

Filed Nov. 21, 1969, Ser. No. 20,209

Term of patent 14 years

Int. Cl. D10—99

U.S. Cl. D52—1

FIG. 2

FIG. 1

FIG. 3

FIG. 4

FIG. 5

FIG. 6

FIG. 1 is a view in side elevation of a fertility timing calculator showing my new design;

FIG. 2 is a top plan view thereof, the cover being removed for convenience of illustration;

FIG. 3 is a side elevation thereof in closed condition;

FIG. 4 is a top plan view thereof of FIG. 3;

FIG. 5 is an end elevation thereof as seen from the right of FIG. 3; and

FIG. 6 is an end elevation thereof as seen from the left of FIG. 3.

I claim:

The ornamental design for a fertility timing calculator, as shown and described.
